(57) CLAIM

The ornamental design for a printer body, as shown and described.

DESCRIPTION

FIG. 1 is a right-front perspective view of a printer body showing the new design;

FIG. 2 is a top view thereof;

FIG. 3 is a front view thereof;

FIG. 4 is a rear view thereof;

FIG. 5 is a right side view thereof; and,

FIG. 6 is a left side view thereof.

The broken lines showing in FIGS. 1-6 are for illustrative purposes only and form no part of the claimed design.
